UNITED STATES PATENT OFFICE

ARTHUR C. ROWLEY, OF DREXEL HILL, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA

ACCELERATING DEVICE FOR DRY PIPE SPRINKLING SYSTEMS

Application filed June 4, 1932. Serial No. 615,443.

This invention relates primarily to devices for use in conjunction with dry pipe systems of automatic sprinkler installations for the purpose of effecting a quick release of air pressure in said system following opening of 5 one or more of the sprinkler heads.

A principal object of the invention is to provide a simple and efficient device of the stated character.

10 Another object is to provide a device of the stated character so constructed that the interior working parts are readily available for cleaning and adjustment.

15 The invention further resides in certain novel structural details and arrangements hereinafter set forth and illustrated in the attached drawing, in which Figure 1 is a vertical sectional view of a device made in accordance with my invention, and Fig. 2 is a 20 transverse sectional view on the line 2—2,

Fig. 1.

With reference to the drawing, my device comprises a casing 1 having an inlet opening 2, which in practice is connected with the 25 dry pipe system, and a discharge or outlet port 3. The casing 1 has an interior chamber 4 within which and depending from a transverse partition 5 is a cylindrical flange 6. The inlet port 2 communicates with the 30 chamber 4 exterior of the flange 6, while the discharge port 3 communicates through a passage 7 with the space in the interior of the flange 6. Movably mounted in the bottom of 35 the casing is a valve 8 which normally engages the lower end of the flange 6 and thereby prevents passage of air from the chamber 4 to the space in the interior of said flange, and hence from the inlet port 2 to the out- 40 let 3.

Mounted in the top of the casing 1 is a dome 11 providing a chamber 12 which is partitioned from the chamber 4 by a flexible dia- 45 phragm 13 secured in the casing. This dia- phragm carries a hollow fitting 14 having a depending stem 15 which projects through an opening in the partition 5 into the space surrounded by the flange 6. The lower end of 50 this stem bears upon the upper face of the valve 8, the stem and diaphragm normally

being supported by the valve in the position shown in the drawing.

Carried by the valve 8 and projecting upwardly into the interior of the hollow stem 15 is a pin 16, said pin being so dimensioned 55 as to provide between its outer surface and the inner wall surface of the stem a restricted passage for air. Secured in and depending from the partition 5 and surrounding the stem 15 is a sleeve 17, the lower edge of 60 this sleeve lying in a plane with the lower edges of the flange 6, so that the said lower edge of the sleeve 17 is also engaged by the valve 8, as illustrated, when the said valve 65 is in the normal elevated position. Space for passage of air is provided between the outer surface of the stem 15 and the inner wall surface of the sleeve 17, and the stem 15 is provided adjacent its lower end and below the 70 upper end of the pin 16 with ports 18 which 75 pass completely through the wall of the stem. Thus, air in the chamber 4 is permitted to pass through an opening or openings 19 in the partition 5 and between the stem 15 and the sleeve 17 to the ports 18 and through said 80 ports to the interior of the stem. The valve 8, however, normally excludes this air from the annular space between the flange 6 and the sleeve 17, which as previously set forth 85 is in communication through the passage 7 with the outlet port 3.

Carried by the fixture 14 and extending from the upper end of the interior passage of the stem 15 is a siphon pipe 21, which as 90 illustrated turns downwardly and terminates 85 at a point adjacent the bottom of the chamber 12. This latter chamber is preferably connected through a fitting 22 with an air pressure gage 23.

In operation, the inlet port 2 is connected 95 with the dry pipe system which contains the sprinkler heads. The latter, in accordance with the usual practice, are normally closed and are adapted to open at a predetermined excessive temperature within the surrounding area. This dry pipe system is also connected with a water supply system, the connection being controlled by a suitable valve normally held closed against the water pressure by air pressure within the dry pipe sys- 100

tem. The said air pressure is transmitted through the port 2 to the interior chamber 4 of the casing 1 and is prevented from passing to the air outlet 3 by the valve 8. When the 5 air pressure is initially applied to the dry pipe system, it acts upon the diaphragm 13 to elevate the fixture 14 and its stem 15, the valve 8 being elevated to its seat against the lower edges of the flange 6 and the sleeve 17 10 by a spring 23 in the bottom of the casing. The air in the chamber 4 as previously set forth is permitted to pass between the sleeve 17 and the stem 15 and through the ports 18 to the interior of the stem, from whence it leaks 15 past the pin 16 into the chamber 12 above the diaphragm. In this manner, the air pressure in the chamber 12 gradually equalizes with the pressure in the chamber 4 and in the dry pipe system, the spring 23, however, being of sufficient strength to maintain the valve 8 in the normal elevated or seated position. If now one or more of the sprinklers of the dry pipe system open, the air pressure in the chamber 4 and at the lower side 20 of the diaphragm 13 immediately falls below the pressure of the air in the chamber 12, which latter pressure is applied to the upper side of the diaphragm. Immediate equalization of the pressure in the chamber 12 with 25 the decreased pressure in the chamber 4 is prevented by reason of the fact that the leakage of air from the dry pipe system and from the chamber 4 is greater than the leakage of air past the pin 16 from the chamber 12 to the chamber 4. Decrease of the pressure below 30 the diaphragm 13, as described, permits the pressure in the chamber 12 to force the diaphragm 13 downwardly, thereby through the stem 15 depressing and unseating the valve 35 8 and permitting rapid escape of air from the chamber 4 and the dry pipe system with which it communicates to the annular space between the flange 6 and the sleeve 17 and through the passage 7 to the outlet port 3. This 40 rapid exhaust of air from the dry pipe system insures a correspondingly rapid decrease in air pressure in the system and insures prompt opening of the valve connecting the dry pipe system with the water supply main. As the water enters the casing 1 45 from the flooded dry pipe system, the water pressure acting against the diaphragm 13 again elevates the diaphragm and the fixture 14 and permits the valve 8 to close, thereby preventing passage of water from the system 50 to the outlet 3. Such small quantities of water as may pass upwardly past the pin 16 into the chamber 12 may be readily withdrawn through the siphon 21. 55

60 It will be understood that with balanced fluid pressures at opposite sides of the diaphragm 13, the spring 23 is sufficient to just overcome the weight of the fixture 14 to thereby permit the valve 8 to seat against the flange 6 and the sleeve 17 whereby only a

small preponderance of pressure in the chamber 12 over that in the chamber 4 is sufficient to cause a downward movement of the diaphragm unseating the valve. The device accordingly is highly sensitive and will operate to exhaust the air from the dry pipe system immediately after the opening of a sprinkler head and the consequent decrease in air pressure in the dry pipe system. The opening of the valve between the water main and the dry pipe system is thus greatly accelerated and insures a prompt supply of water to the sprinkler system. 70

It will be noted that the bottom of the casing 1 is formed by a removable fitting 24 which constitutes a cylinder for the valve 8 and insures proper location of the latter with respect to the flange 6 and the sleeve 17. The fitting is threaded into the casing 1, and when removed affords ready access to the interior of the housing and to the valve. The pin 16 is secured in a recess in the valve by a threaded plug 25, the lower projecting portion of the valve into which this plug threads constituting a retainer for the spring 23, which latter seats in the bottom of the fitting 24. The body of the valve 8 is formed with an annular recess at the top for a suitable material, such as rubber or fibre, which being relatively soft forms an adequate seal at the lower edges of the flange 6 and the sleeve 17. The diaphragm is confined at its peripheral edge between an annular seat 26 in the casing 1 and a retaining ring 27, the latter being clamped down upon the diaphragm by the dome 11. At its center the diaphragm is clamped to the fitting 14 by a retaining ring 28 and nut 29, both threaded on the upper extension of the said fitting. The device is characterized by extreme compactness and simplicity of assembly and is highly efficient in operation. 85

As described above, the device is employed as an exhauster for the dry-pipe system, but it will be apparent that by connecting the outlet port 3 with the intermediate chamber of the dry-pipe valve which connects the water main to the dry-pipe system, while the port 2 is connected to said system as described above, the device may constitute an "accelerator" 110 functioning when a sprinkler head opens to equalize the pressures at the opposite sides of the dry-pipe valve clapper and thereby destroying the ability of the valve to hold back the water from the system. The device, therefore, is essentially both an exhauster and an accelerator, depending upon the manner in which it is connected in the system. 115

I claim:

1. In a device of the stated character, the combination with a housing, of a flexible partition defining independent chambers within said housing, one of said chambers having inlet and outlet ports, a valve normally closing said outlet port, a hollow stem 125

carried by the partition and forming a passage between said chambers, a pin carried by said valve and projecting into said stem to restrict said passage, means normally retaining said valve seated, and means whereby movement of the said partition due to unbalanced pressures in said chambers effects through said stem an unseating of the valve establishing communication between said inlet and outlet ports.

2. In a device of the stated character, the combination with a housing, of a flexible element secured in said housing and dividing the interior thereof into independent chambers, the first of said chambers having inlet and outlet ports, a hollow stem depending from said flexible element into said first chamber and constituting a passage through which said chambers communicate, ports in said stem affording a continuous connection between the interior of the stem and said first chamber, spaced partitions surrounding said stem and providing an annular space within said first chamber through which said chamber communicates with said outlet port, a valve adapted when seated to seal said space from the chamber, resilient means normally retaining said valve seated, a pin carried by said valve and projecting into the interior of said stem above said stem ports to restrict said passage, said parts being so constructed and arranged that deflection of said partition due to a preponderence of pressure in the second chamber effects an unseating of the valve to thereby establish direct connection between the said inlet and outlet ports.

3. In a device of the stated character, the combination with a housing, of a flexible element secured in said housing and dividing the interior thereof into independent chambers, said element having a hollow depending stem constituting a communicating passage between said chambers, openings in said housing constituting inlet and outlet ports for the first of said chambers, spaced partitions in the last-named chamber surrounding said stem and providing therebetween a space communicating with said outlet port, a valve normally sealing said space from said first chamber and constituting a seat for said stem, means providing for communication between the interior of said stem and the said first chamber, a pin carried by said valve and extending into the interior of said stem to restrict said passage, and means for normally holding said valve seated, said parts being so constructed and arranged that a preponderance of pressure in the second chamber effects a movement of the diaphragm which acting through said stem unseats the valve to thereby establish direct connection between said inlet and outlet ports.

4. In a device of the stated character, the

combination with a housing, of a flexible element secured in said housing and dividing the interior thereof into independent chambers, a hollow stem depending from said partition into one of said chambers and constituting a passage connecting said chambers, a member in said second chamber having an opening through which said stem extends, flanges depending from said member at the edge of said opening and embracing said stem, said flanges being separated to form therebetween a space communicating with the last-named chamber, a valve adapted to engage the lower edges of said flanges to seal said space from the chamber, said valve constituting also a support for said stem, means for resiliently retaining the valve on its seat upon said flanges, means providing for communication between the last-named chamber and the interior passage of said stem, a pin carried by said valve and projecting into said passage to restrict the latter, said housing having ports communicating respectively with the last-named chamber and with the space between said flanges, said ports being disconnected one from the other when said valve is seated and having communication with each other when the valve is unseated.

5. In a device of the stated character, the combination with a housing, of a flexible diaphragm secured in said housing and dividing the interior thereof into upper and lower chambers, a hollow stem depending from said diaphragm and constituting a passage through which said chambers communicate, annular radially spaced partitions embracing said stem and forming an annular chamber open at the bottom for communication with said lower chamber, the housing having ports communicating respectively with the last-named chamber and the chamber formed by said annular partitions, a valve adapted to seat on the lower edges of said partitions to seal the chamber therebetween from said lower chamber, said valve forming a bearing for said stem, openings in the stem providing for communication between the interior of said stem and said lower chamber, a pin carried by the valve and projecting into the stem above the last-named ports to restrict the stem passage, and a spring for normally retaining said valve seated, said parts being so constructed and arranged that a pressure in said upper chamber exceeding the pressure in the lower chamber causes a movement of the diaphragm which through the medium of said stem unseats the valve to afford direct communication between said housing ports.

ARTHUR C. ROWLEY.
